HAROLD E. HOUSEMAN, OF WILMINGTON, DELAWARE, ASSIGNOR TO STANDARD-
TRUMP BROTHERS MACHINE COMPANY, OF WILMINGTON, DELAWARE, A COR-
PORATION OF DELAWARE.

CIRCULAR-KNITTING MACHINE.

Application filed December 3, 1924. Serial No. 753,562.

In circular knitting machines adapted for the manufacture of hosiery, means have been devised to produce longitudinal stripe effects along both the front and rear of the 5 stocking and along the top of the foot, while eliminating such effects from the heel, toe and bottom of the foot. One known means of producing a stripe is to knit the stocking of two threads, one of which is known 10 as a body yarn and the other of which is known as a plating yarn. These threads are differently positioned, but those (regular) needles that are not to produce the striping effect are drawn down at such a 15 point in the rotation of the needle cylinder that the needles will engage both threads and knit them in together. Those (special) needles that are to produce the striping effect are drawn down in advance of the point 20 at which the regular needles are drawn down, and are drawn down at such a point that they will engage one of the threads but not the other. The thread that is not engaged will therefore float across the fabric 25 and only the thread that is engaged by the special needles will form loops.

The special needles above mentioned are usually equipped with extra butts, or jacks are secured thereto. This involves a lengthening 30 of the needles, a consequent lengthening of the needle cylinder, and the provision of special cams for operating the extra butts or jacks and special mechanism for operating these cams. This involves not only 35 additional expense, but also a substantial addition to the needle operating mechanism. It is also well known that machines so equipped for producing such striping effects must be operated at a reduced speed, 40 thereby reducing production.

The objects of my invention are to produce essentially the same fabric by means of simplified striping needles that can be manufactured at no higher cost than the 45 regular needles, to avoid the necessity of elongating the needle cylinder, to avoid the provision of any additional needle actuating cams and also any additional cam actuating mechanism (although a change in the 50 construction of one of those cams and its actuating mechanism is contemplated) and to make possible the safe operation of the machine at the same speed as it is possible

to safely operate a machine equipped to knit a plain fabric. 55

The invention has other advantages and possibilities, which will be mentioned hereinafter.

A preferred embodiment of invention is shown in the accompanying drawings, in 60 which—

Fig. 1 is an elevation showing a number of the needles, the needle actuating cams and the yarn fingers.

Fig. 2 is a vertical section through the 65 needle cylinder, the stitch cam and the mechanism for operating the latter.

Figs. 3 and 4 are fragmentary vertical sections showing the stitch cam in the position it occupies during the knitting of the 70 foot; Fig. 3 showing a special or striping needle of the rear bank and Fig. 4 a regular needle of the rear bank.

Fig. 5 is a diagram of the needle cylinder illustrating a typical distribution of the 75 regular and special needles of both banks.

Fig. 6 is a diagram showing a stocking, cross-sections through different parts of the stocking, and the relative positions of the 80 four different kinds of needles and the stitch cam during the knitting of each part.

Fig. 7 is a diagram, enlarged, of a small section of striped fabric.

Fig. 8 is a developed view of the pattern cam for controlling the position of the 85 stitch cam.

Fig. 9 is an elevation of a modified arrangement of cams.

Vertically slidable in the rotatable needle cylinder *a* are the needles (hereinafter particularly described). In Fig. 1, one of the 90 yarn carriers *b* is shown projected into the throat of the latch ring *c*, in position to enable yarn fed therefrom to be engaged by the needles. In the same figure is shown a group of cams, which are constructed and 95 arranged in the usual way except that the construction of the stitch cam *d* has been modified, as hereinafter described. The stitch cam *d* is operable by known mechanism: namely, a slide *e* movable radially inward by means of a spring *f* and movable 100 radically outward by means of a bell crank lever *g*; the latter being swingable by means of a vertically movable post *h*, which is actuatable by a cam on a pattern disc *i*. Sub-

stantially this same mechanism for operating the stitch cam is shown in certain patents: for example, the H. A. Houseman Patent No. 1,207,757, dated December 12, 1916, except that in the present machine there is provided a special cam (shown developed in Fig. 8) on the pattern disc and herein-after described.

Before describing the novel elements of my invention, I will first more particularly describe the customary means for forming longitudinal stripes referred to in general language in the introductory part of this specification. From the yarn carrier *b* are fed two yarns, one a body yarn 10 and the other a plating yarn 11 (see Fig. 1). The regular needles and the special (striping) needles approach these yarns at the same height, but the special needles start to move down at a point in advance of the point at which the regular needles start to move down. The positions of the two yarns 10 and 11 are such that the hooks of the regular needles, in their downward movement, successively engage both yarns 10 and 11, while the hooks of the special needles, after engaging one of the yarns, say the body yarn 10, start to move down so far in advance of the point at which the regular needles start to move down that the special needles do not engage the plating yarn 11. The plating yarn 11 is therefore not knit into the fabric, but floats across it. This is shown in Fig. 7, which illustrates, diagrammatically, the structure of the fabric produced by positioning two special or striping needles between two series of regular needles. Looking toward the outside face of the fabric, the body yarn 10 is largely concealed by the plating yarn 11, except along the wales wherein the loops are formed wholly by the body yarn 10. In that part of the fabric, the more conspicuous yarn is the body yarn. Obviously, if these two yarns are of different color, or are otherwise differentiated, the effect produced is that of a stripe.

I will now proceed to describe the novel elements of my invention: namely, the needles, the stitch cam and the cam on the pattern disc for controlling the positions of the stitch cam.

As usual, there are provided two banks of needles, one-half of which (which I shall call the front bank) are adapted to knit the front half of the leg and the top of the foot, and the other half of which (which I shall call the rear bank) are adapted to knit the rear half of the leg, the heel, the bottom of the foot, and the toe. The regular needles of the front bank are lettered *m*; the special needles of the front bank are lettered *n*; the regular needles of the rear bank are lettered *o*; and the special needles of the rear bank are lettered *p*.

All the needles of the front bank are pro-

vided with long butts *r*, but each of the special needles *n* is also provided with a shoulder *s* above its butt. All the needles of the rear bank are provided with short butts *t*, but each of the special needles is also provided with a shoulder *u* above its butt. The shoulders *s* of the special front needles *n* are wider than the shoulders *u* of the special rear needles *p*.

The stitch cam *d* is widened, at its upper forward corner, to provide a part *v* overhanging the inner side of the cam. This overhanging part has a cam face aligning with the regular cam face of the cam and is in effect a supplemental cam. See Figs. 80 1-4 and Fig. 6.

In knitting striped hosiery, it is customary to knit a short length of plain, or unstriped welt *w* (see Fig. 6). To knit this welt, the stitch cam is moved radially out until supplemental cam *v* entirely clears the shoulders *s* and *u* of the special needles of both banks, but so that cam *d* engages both the long and short butts of all the needles, as shown in position I of Fig. 6. In this position of the stitch cam, all the needles will be operated at the same point in the circumference of the needle cylinder; and the downward movement of the special needles, as well as of the regular needles, will be delayed until they are in a position to engage both yarns 10 and 11.

In knitting the stocking leg *x*, it is usually desirable to form stripes both on the front and the rear of the stocking, for which reason the special needles, above described, are provided in both front and rear banks. Preparatory to knitting the leg, between the welt and the ankle, the stitch cam is moved radially to its extreme inward position, as shown in Fig. 2, and in position II in Fig. 6. In this position of the stitch cam, the supplemental cam *v* is in line of travel of the shoulders (*s* and *u*) of all the special needles (front and back). These shoulders will be engaged by the supplemental cam *v* before the main cam *d* is engaged by the butts of the regular needles, as shown in Fig. 1. Hence, all the special needles will move down at a point in the circumference of the needle bed in advance of the point at which the regular needles are moved down and hence will engage only the body yarn 10 and miss the plating yarn 11, as hereinbefore described and as will be clear by an inspection of Fig. 1. Therefore, longitudinal stripes will be formed on the front and back of the stocking.

Preparatory to knitting the heel, it is desirable to knit a short length of circular fabric *y*, from the rear of which the striping effect is omitted. To effect this, the stitch cam is moved radially outward just sufficiently to cause the supplemental cam *v* to clear the narrow shoulders *u* of the special needles 130

p of the rear bank, but not sufficiently to clear the wider shoulders *s* of the special needles *n* of the front bank, as shown in Fig. 3, and more clearly at position III of Fig. 6. Consequently, only the special needles *n* of the front bank will be engaged by the cam *v* and only these needles will be given a premature downward movement as they move opposite the yarn carrier, and hence stripes will be formed on the front of the stocking and not on the rear.

In order to knit the heel *z*, the front bank of needles is moved up out of action in the usual way. Actuating mechanism for so moving the needles *m* and *n* out of action is not herein shown, and forms no part of my invention, but is well known in the art. The inoperative position to which the needles *m* and *n* are moved is shown at position IV of Fig. 6. The radial position of the stitch cam remains unchanged and as the supplemental cam *v* is not in position to engage the shoulders *u* of the special needles *p*, no stripes will be formed in the heel.

In knitting the body *y'* of the foot the front needles *m* and *n* are restored to operative position, the radial position of the stitch cam remains unchanged, and the fabric is knit with stripes on the top of the foot but not in the sole. In other words, the same fabric is knit at *y'* as at *y*. See position V of Fig. 6.

In knitting the toe *z'*, the front bank of needles is moved up out of action, as in knitting the heel *z*. The position of the stitch cam remains unchanged, and a plain fabric is formed in the toe as in the heel.

As hereinbefore described, the radial position of the stitch cam is controlled by a cam-way carried by the pattern disc *i* and shown developed in Fig. 8. When the high part 20 of this cam underrides the post *h*, the stitch cam is moved radially to its extreme outward position, thereby clearing the butts of all the needles and permitting them to be levelled. As the pattern disc cam advances, part 21 underrides post *h*, allowing spring *f* to move the stitch cam into position I of Fig. 6. After the welt is knit, part 22 of the pattern disc cam underrides post *h* and allows it to drop to its lowest position, permitting spring *f* to move the switch cam into its extreme inward position, as shown at position II of Fig. 6. After the leg is knit, part 23 of the pattern disc cam underrides post *h* and lifts it so as to effect a slight outward movement of the stitch cam, as shown at positions III, IV, V and VI of Fig. 6. This part 23 of the pattern disc cam underrides the post *h* during the knitting of the remainder of the stocking. The part 24 of the pattern disc cam then draws the stitch cam to the same position that it occupied while under control of part 21, so as to provide for the knitting of a few courses of plain circular knitting. Part 25 of the pattern disc cam then draws the stitch

cam to the same position it occupied while under control of part 20, that is, into position to clear the butts of all the needles and allow the needles to be levelled.

From the foregoing description, it will be evident that my special needles can be manufactured as cheaply as my regular needles. I have done away with extra butts, or special jacks, and with the additional mechanism for operating the same, and have avoided the necessity of lengthening the needle cylinder to accommodate these jacks or extra butts. It should be noted that my invention involves the use of no additional mechanism whatever. A stitch cam, pattern means and intermediate actuating mechanism are necessary parts of the regular mechanism of a machine equipped only to effect plain knitting. I retain this actuating mechanism unchanged and modify the construction of the stitch cam and the pattern means, but without adding any parts. I am thus able to convert a machine adapted for plain knitting into a machine adapted to knit a striped stocking of any design with the stripes in any desired part of the stocking, without really adding any mechanism. This not only saves expense and avoids the liability to getting out of order which is incidental to the introduction of additional complications into a machine which is already sufficiently complicated, but I find that the machine can be operated as rapidly as machines adapted for plain knitting, which is an advantage that is believed to be novel and is certainly important.

It should be understood that my invention is not limited to any special arrangement of the described regular and special long-butt and short-butt needles, nor to such an arrangement of the needles as will produce the striping effects described. As an example of one of many possible modifications, a stocking can be made of a single yarn and the stripe may be an open-work stripe produced by floating the yarn across the fabric for a width of one or more wales. Such a fabric would be illustrated in a drawing like Fig. 7 except for the omission of the body yarn 10. This would involve a simplification of my invention, and would be within its broader, but not its more specific, scope.

A very useful adaptation of the invention is to double sole knitting. In knitting an extra thread in the sole, great difficulty is experienced in producing an even splicing line. By means of my invention, the extra thread may be caused with certainty to engage the same needle at each rotation of the machine, thereby producing an even splicing line.

Still other useful adaptations of the same broad invention may be made. For example, it is often desirable to move certain

needles out of action so that they will not be actuated by the stitch cam to engage any yarn that is fed to the needles; say, for example, in the production of open-work in 5 hosiery in which both a body yarn and a plating yarn is knit into the fabric. To attain this end, a special cam may be provided that is movable independently of the stitch cam, and this special cam may be so 10 positioned as to engage the shoulders of shouldered needles before such needles reach the regular set of cams, so that all such needles will be depressed and be carried under all the cams and therefore fail to engage the yarn.

An adaptation of the invention to accomplish this purpose is shown in Fig. 9. In Fig. 9, 40 is the regular set of cams, of 15 which 41 is the stitch cam, which may be identical with stitch cam *d v* or may be a stitch cam of usual construction. 42 is a special cam movable (say vertically in guides in a frame 43) into and out of operative position to engage the needle shoulders. In the full line position shown, the cam 42 is so positioned as to miss the butts of all the needles, so that the needles 50 unprovided with shoulders move toward the regular cams at the normal level; but, in 20 such position of the cam 42, it engages all the shoulders of all needles 51 that are provided with shoulders and depresses them so that they move toward the regular cams at a level below normal, or at such a level that 25 they will be engaged by the end cam 44 and be carried below all the cams and not engage the yarn. When it is desired to render the cam 42 inoperative, it is moved into the position shown in dotted lines.

Having now fully described my invention, 40 what I claim and desire to protect by Letters Patent is:

1. In a circular knitting machine, the combination of yarn feeding mechanism, 45 needles provided with butts and some of which are provided with shoulders substantially shorter than the butts, certain of said shoulders being shorter than other shoulders, a stitch cam adapted to engage needle butts to effect the depression of the needles, 50 the stitch cam having an overhanging portion forming a supplemental cam adapted to engage the shoulders of shouldered needles to effect their depression at a point sufficiently in advance of the point of depression of other needles to cause shouldered 55 needles to escape knitting engagement with the yarn, said stitch cam being movable into one position to cause its supplemental cam to engage the shoulders of all the shouldered needles and into another position to cause its supplemental cam to engage only the wider shoulders and into still another position to cause its supplemental cam to escape 60 engagement with all the shoulders, and pattern mechanism controlling the position of the supplemental cam.

tern mechanism controlling the position of the stitch cam.

2. In a circular knitting machine, the combination defined in claim 1 in which the 70 yarn feeding mechanism comprises also means to so differentially position a second yarn that it will be engaged by prematurely depressed needles as well as by the remaining needles, thereby causing all the needles to knit one yarn into the fabric while a selected portion of the needles fails to knit the other yarn into the fabric.

3. In a circular knitting machine, the combination defined in claim 1 in which the 80 needles are arranged in two arcuate groups in one of which are included all the needles having wider shoulders and in the other of which are included all the needles having narrower shoulders, the needles of the first group having longer butts than the needles 85 of the second group and being movable out of action to allow the knitting to proceed only on needles of the second group.

4. In a circular knitting machine, the combination of yarn feeding mechanism, 90 regular needles provided with butts, special needles provided with butts and with shoulders substantially shorter than the butts, a stitch cam adapted to engage needle butts to effect the depression of the needles, 95 the stitch cam having an overhanging portion forming a supplemental cam adapted to engage the shoulders of special needles to effect their depression at a point sufficiently in advance of the point of depression of the regular needles to cause the special needles to escape knitting engagement with the yarn, said stitch cam being movable into positions into and out of the path of travel of said shoulders, thereby effecting 100 the knitting engagement, in one position of the cam, of only the regular needles with the yarn, and, in another position of the cam, of all said needles with the yarn, and pattern mechanism controlling the position of the stitch cam.

5. In a circular knitting machine, the combination of yarn feeding mechanism, regular needles provided with butts, special needles provided with butts and also with 115 shoulders substantially shorter than the butts, a stitch cam adapted to engage needle butts to effect depression of the needles, a supplemental cam adapted to engage the shoulders of special needles to effect their depression at a point sufficiently in advance of the point of depression of the regular needles to cause the special needles to escape knitting engagement with the yarn, said supplemental cam being movable out of and 120 into the path of travel of said shoulders, whereby all the needles or only the regular needles will knit the yarn into the fabric, and pattern mechanism controlling the position of the supplemental cam.

6. In a circular knitting machine, the combination with regular needles and special needles, of a radially movable stitch cam adapted to depress all the needles, and cooperating means carried respectively by the stitch cam and the special needles adapted, when the stitch cam is in one radial position, to effect the depression of both regular and special needles while at the same time 10 effecting the depression of the special needles at a point in advance of the point of depression of the regular needles, and pattern mechanism controlling the movement of the stitch cam into and out of the last named 15 position.

7. In a circular knitting machine, the combination with needles provided with butts and some of which are provided with shoulders above the butts, of a stitch cam adapted 20 to engage said butts and depress the needles and provided with an overhanging portion in the path of travel of said shoulders and adapted to engage said shoulders at a point in advance of the engagement 25 with the butts, thereby effecting the depression of the shouldered needles at a point in advance of the point of depression of the remaining needles.

8. In a circular knitting machine, the combination with rotatable needles provided 30 with butts and with shoulders above the butts, of a stitch cam having a downwardly inclined face, the upper part of the stitch cam being wider than the lower part, the 35 overhanging upper part of the cam face being in the path of travel of the needle shoulders and adapted to engage them and lower the needles until the shoulders ride below said overhang, the butts thereafter 40 engaging the face of the cam below said overhang and completing their movement of depression.

9. Circular knitting machine mechanism in accordance with claim 8, in combination 45 with means to move said cam into position to bring the overhanging upper part of the cam face out of the path of travel of the needle shoulders, thereby delaying the movement of depression of the needles until their 50 butts engage said cam.

10. The construction defined in claim 8, in combination with other unshouldered needles provided with butts that engage the stitch cam beyond the point of engagement 55 with the stitch cam of the shoulders of the shouldered needles.

11. In a circular knitting machine, the combination with needles, of yarn feeding mechanism adapted to differentially position 60 two threads so that both of them will be engaged by needles movable downward at one point in the circumference of the needle cylinder and only one of them will be engaged by needles movable downward at an 65 advance point in the circumference of the

needle cylinder, a stitch cam, cooperating means on the needles and stitch cam adapted to effect the depression of the needles at one point or the other dependent on the position of the stitch cam, and pattern controlled means to move the stitch cam into one or the other of said positions.

12. In a circular knitting machine, the combination with two sets of needles provided with respectively different cam-engaging elements, of stitch cam mechanism movable into one position to effect the simultaneous downward movement of needles of both sets and into another position to effect the downward movement of needles of one set at a 75 point in advance of the point of downward movement of needles of the other set, and yarn feeding mechanism adapted to so differentially position two threads that both 80 of them will be engaged by the needles of both sets when the cam mechanism is moved into the first position and only one of them will be engaged by the needles of both sets when the cam mechanism is in the second 85 position.

13. In a circular knitting machine, the combination with needles each provided with two cam-engaging elements, of a cam adapted, dependent on its position, to either engage one only of said elements or engage 90 both elements successively, and means to shift the cam into either of said specified positions.

14. In a circular knitting machine, the combination defined in claim 8 in which the 100 cam is movable substantially radially with respect to the needles.

15. In a circular knitting machine, the combination with rotatable needles provided with butts and with shoulders above the 105 butts, of a stitch cam one part of which has a downwardly inclined face and the other part of which has a downwardly inclined face constituting a continuation of the first named downwardly inclined face, a limited 110 portion of the width of the first named downwardly inclined face being in the path of travel of the needle shoulders and adapted to engage them and lower the needles until the shoulders ride below it, the butts thereafter 115 engaging the second named downwardly inclined face and completing their movement of depression.

16. The construction defined in claim 15 in combination with other unshouldered needles provided with butts that engage the stitch cam at a point in the circle of needles beyond the point of engagement with the stitch cam of the shoulders of the shouldered needles.

17. In a circular knitting machine, the combination with a slotted needle cylinder, of needles each having a butt and a shoulder above the butt, the butts extending a substantially greater distance than the shoulders 120 125

beyond the slots of the needle cylinder, and cam members adapted to cooperate the lower needles by acting successively upon their butts and also adapted to lower needles by 5 acting one upon their shoulders and the other upon their butts.

18. In a circular knitting machine, the combination with a slotted needle cylinder, of needles each having a butt and a shoulder 10 above the butt, the butts extending a substantially greater distance than the shoulders be-

yond the slots of the needle cylinder, and cams one of which is adapted to lower needles by acting upon their shoulders and another of which is adapted to lower needles 15 by acting upon only their butts.

In testimony of which invention, I have hereunto set my hand, at Philadelphia, Pennsylvania, on this 25th day of November, 1924.

HAROLD E. HOUSEMAN.
